UNITED STATES PATENT OFFICE.

WILLIAM KOENIGS, OF PATERSON, NEW JERSEY, ASSIGNOR, BY MESNE ASSIGNMENTS, TO EDWARD M. KNOX, OF NEW YORK, N. Y.

DESIGN FOR A HAT-BAND.

SPECIFICATION forming part of Design No. 33,319, dated October 2, 1900.

Application filed August 21, 1900. Serial No. 27,630. Term of patent 3½ years.

To all whom it may concern:

Be it known that I, WILLIAM KOENIGS, a citizen of the United States, residing at Paterson, county of Passaic, and State of New Jersey, have invented and produced a new and original Design for Hat-Bands, of which the following is a specification, reference being had to the accompanying drawings, forming a part hereof.

10 Figure 1 is a plan or face view of a portion of a hat-band, showing my new design enlarged. Fig. 2 is a sectional view of the central portion of the hat-band enlarged. Fig. 3 is a sectional view of one of the borders of the hat-band enlarged.

15 As shown in the drawings, the leading or

material feature of my design consists of a middle portion having transverse ribs and provided with two borders, substantially as shown, having dots and dashes arranged in a running pattern upon a finely-ribbed ground, substantially as illustrated.

Having described my invention, what I claim as new, and desire to secure by Letters Patent, is—

The design for a hat-band, substantially as shown and described.

WILLIAM KOENIGS.

In presence of—

JAMES M. STEWART,
S. S. SHERWOOD.
